UNITED STATES PATENT OFFICE.

JOHN C. SCHAEFER AND JOHN A. HAGMAYER, OF NEW YORK, N. Y.

SAFETY-VALVE FOR BEER-CASKS.

SPECIFICATION forming part of Letters Patent No. 337,622, dated March 9, 1886.

Application filed July 16, 1885. Serial No. 171,775. (No model.)

To all whom it may concern:

Be it known that we, JOHN C. SCHAEFER and JOHN A. HAGMAYER, citizens of the United States, residing at New York, in the county 5 and State of New York, have invented new and useful Improvements in Safety-Valves for Beer-Casks, of which the following is a specification.

Our invention relates to improvements in 10 safety-valves for beer-casks; and it consists in an improvement on the invention described in Letters Patent No. 318,040, granted to John C. Schaefer, and dated May 19, 1885, whereby the valve is rendered more efficient and reliable, and allows the use of oil or similar fatty 15 lubricants.

The novel features of our present invention are fully pointed out in the following specification and claims, and illustrated in the accompanying drawings, in which—

Figure 1 is a side view, partly in section, of our improved safety-valve. Fig. 2 is a longitudinal vertical section thereof. Fig. 3 is a section of one of its parts.

25 Similar letters indicate corresponding parts. In the drawings, the letter A designates the valve-shell, having a hole or passage, b, opening upward, Fig. 2, the edge of which constitutes the seat for a valve-disk, B, of a valve, 30 B', and it has also a second hole or passage, c, opening upward, the edge of which constitutes the seat for the rubber disk or diaphragm C of a relief-valve, C'. The hole or passage c is larger in diameter than the hole or passage b, and the diaphragm C is held to its seat 35 by the valve-stem c', the lower end of which has a turned portion or disk, c'', which fits into a collar, c''', so as to be capable of longitudinal motion therein, and bears upon the 40 aforesaid disk or diaphragm. The valve-disk B is also arranged on the lower end of a valve-stem, b', and both stems are attached to a lever, D, carrying an adjustable weight, D'.

On the upper portion of the valve-shell A, 45 and surrounding the valve-stems, is cast or secured a cup or vessel, E, which communicates with the interior of the valve-shell through the outlet-orifices F, formed in the cover b'' of the valve-shell which surrounds the valve-stem b', and the cup or vessel also communicates with the interior of the cover c' of the

shell which surrounds the stem c' through similar orifices, F', in the said cover.

One end of the valve-shell communicates with a branch, G', of a storage-chamber, G, which latter is also provided with a second lateral branch, G'', having therein a stop-cock, H, for transmitting air into the beer-casks should undue pressure arise from the pump, which will occur if a chip gets before the racking cock and stops the stream of beer from getting out. The chamber is likewise provided with a longitudinal branch, I, which is partly screw-threaded to engage with the corresponding threaded bush of the cask.

In applying the valve to use, the cup or vessel E is supplied with water or oil, which thence flows through the orifices F into the valve-shell, and acts as a lubricant to the valve-seat and disk B, so that the danger of "gumming" or "fouling" of the valve is thus effectually obviated. The water or oil also enters the cover c' and fills the interior of the same. In order to keep the water or oil from flowing into the beer or other liquid in the cask 65 through the branch I, Fig. 2, we form a diaphragm, J, in the storage-chamber, which emanates from the branch G' and extends upward in the chamber above the level of the upper edge of the cup or vessel E. The water or oil flowing through the holes F in the cover b'' of the valve-shell completely fills the interior of the valve-shell, and rises in the channel formed between the diaphragm J and the wall of the chamber up to the level of 75 the water in the cup or vessel.

It will be observed that the cover C' is screwed down so that its lower edge impinges on the collar c''' in order that the rubber diaphragm cannot lift from the seat.

The action of the valves is as follows: If by any means an excess of pressure occurs in the cask the elastic disk or diaphragm of the relief-valve C', having a larger area than the valve-disk B, will be first bulged upward in 95 its center, and lifts the valve-stem, whereby the pressure due to the weight of the weighted lever will be thrown completely off the valve B, and the latter will be raised from its seat and so held until the pressure falls to its normal figure.

The object of our present invention is to

render it impossible for the water, oil, or other lubricant to find its way into the cask, which was liable to occur in the safety-valve described in the above-mentioned patent, for the reason that in the patent the plate forming the dam does not and cannot extend up above the cup or vessel or above the level of the liquid therein if the cup or vessel be filled.

From the drawings and description it is evident that in our present invention it is impossible for the lubricant to back into the cask, as it cannot pass over the diaphragm J, as the latter rises in the storage-chamber to a point above the cup or vessel, or above the level of the oil therein if the cup or vessel be filled to or near its top, and consequently oil or similar fatty lubricants can be employed in this valve without danger of deterioration to the liquid in the cask. It will also be observed that by placing the cup or vessel E above the valve-shell, and having the diaphragm in the storage-chamber, both the upper and lower faces of the valve-disks and also part of the stems are completely surrounded by the lubricant. In order that the lubricant can be emptied from the vessel and valve shell or only from the valve-shell, if desired, and also that access may be had to the shell for cleaning purposes, we provide one end of the latter with a plug, K, which can be easily removed and the liquid allowed to run out from the shell, and when the liquid in the vessel is also to be emptied the valve must be lifted and held from its seat.

Another object of our present invention is to secure greater reliability and promptness in the action of the valve, and for this purpose we introduce the secondary or relief valve C', with its elastic disk or diaphragm. It is evident that the said relief-valve could be entirely dispensed with without interfering with the action of the valve B; but for the reasons above given we prefer the use of the relief-valve in combination with the latter.

To observe the pressure in the chamber, an ordinary pressure-gage can be secured to the top of the same.

What we claim as new, and desire to secure by Letters Patent, is—

1. The combination, with the valve-shell A and the lubricating cup or vessel E, having a

valve-seat and a weighted disk, B, of the perforated cover b², arranged in the lubricating cup or vessel, the storage-chamber G, and the diaphragm J, rising from the valve-shell in the storage-chamber to or above the level of the upper portion of the lubricating cup or vessel, substantially as and for the purpose described. 55

2. The combination, substantially as hereinbefore described, with the valve-shell and the chamber, of the valve-seat, the weighted valve-disk B, the lubricating cup or vessel communicating with the outlet-orifice of the valve, and the diaphragm extending upward from the valve-shell to or above the level of the upper edge of the cup or vessel. 60

3. The combination, with the valve-shell and the chamber, of the weighted valve-disk, the lubricating cup or vessel on the valve-shell, the outlet-orifices in the cover opening into the said vessel, and the diaphragm in the chamber extending upward from the valve-shell to or above the plane of the upper edge of the vessel, substantially as shown and described. 70

4. The combination, substantially as hereinbefore described, with the valve-shell and the chamber, of the valve-seats b and c, the disk B, fitting the seat b, the weighted relief-disk C, fitting the seat c, the cup or vessel connecting with the valve-shell, and the diaphragm in the chamber. 80

5. The combination, substantially as hereinbefore described, with the valve-shell and the chamber, of the valve-seats b and c, the disk B, fitting the seat b and connected to a weighted lever, the elastic disk or diaphragm C on the seat c, connected with and sustaining the weight of the lever, the cup or vessel communicating with the valve-shell, and the diaphragm in the chamber extending upward from the valve-shell to or above the level of the upper edge of the cup. 85 90

In testimony whereof we have hereunto set our hands in the presence of two subscribing witnesses. 95
